UNITED STATES PATENT OFFICE

105,554

DESIGN FOR A ROBE

Victoria Malhame, New York, N. Y.

Application June 23, 1937, Serial No. 70,020

Term of patent 3½ years

To all whom it may concern:

Be it known that I, Victoria Malhame, a citizen of the United States of America, residing in Manhattan, county of New York and State of New York, have invented a new, original, and ornamental Design for a Robe, of which the following is a specification, reference being had to the accompanying drawing, forming part thereof, wherein,

The characteristic feature of my design resides in the combination on the collared robe as shown of a contrastingly colored insert panel in the front section extending from the hem to collar and tapering to a point at the neckline as shown.

I claim:

The ornamental design for a robe, substantially as shown, and described.

VICTORIA MALHAME.
